UNITED STATES PATENT OFFICE.

DMITRY NICOLAJEWITSCH ALEXEEFF, OF MOSCOW, RUSSIA.

PROCESS FOR MAKING AND PLACING CONCRETE FILES.

1,202,954.

Specification of Letters Patent.

Patented Oct. 31, 1916.

Application filed August 29, 1912. Serial No. 717,749.

To all whom it may concern:

Be it known that I, DMITRY NICOLAJEWITSCH ALEXEEFF, a subject of the Emperor of Russia, residing at No. 14 Krasnoprudnaja street, Moscow, in the Government of Moscow, Russia, have invented a new and useful Improved Process for Making and Placing Concrete Piles, of which the following is a specification.

10 This invention relates to a process for the construction of concrete piles by driving in a driving pile which draws with it a protective tube. According to this invention, after the withdrawal of the driving pile 15 there is inserted in the protective tube in combination with its reinforced edge, a directing tube, into which the concrete is rammed while the protective tube together with the directing tube are gradually withdrawn. This process has in comparison with 20 those already known the considerable advantage that one and the same protective tube can be used for the production of any number of concrete piles, because it does 25 not remain in the earth. The use of the inner directing tube has moreover the advantage that in consequence of the interspace between the directing and the protective tube when the concrete is rammed in the 30 directing tube begins to shake and the friction of the concrete on the inner surface of the tube and consequently the work of ramming it down is diminished.

In the accompanying drawing is illustrated 35 a construction for carrying the invention into effect.

Figure 1 is a longitudinal section through the protective tube with the driving pile inserted. Fig. 2 shows in front view the directing tube to be inserted in the protective tube after the withdrawal of the driving pile. Fig. 3 shows the collar serving for the withdrawal of the protective tube, and Fig. 4 the block which serves for ramming. Fig. 45 5 shows a longitudinal section through the protective tube with the directing tube inserted.

This process for the construction of concrete piles is adapted for any soil which 50 permits of the ramming of piles. The process consists essentially in placing a wood or metal pile A (Fig. 1) provided below

with a metal shoe B which has a heel-piece C inside a protective tube, in the lower part whereof there is secured an annular insertion which is so formed that the heel C of the shoe B presses against it. Thereupon the pile A is driven into the ground by means of an ordinary pile driver, and carries the protective tube D with it. When the 55 resistance of the ground is sufficient the pile A is drawn out of the tube D and into the latter there is inserted a directing tube F (Figs. 2 and 5) the internal diameter of which is equal to the opening in the part E 60 (Fig. 1). The lower part of the tube F has a reinforcement C, by means of which the tube presses upon the part E (Figs. 1 and 5). There is moreover at the upper part of the protective tube A a clamping device H 65 (shown in front view in Fig. 3) by aid of which the protective tube can be gradually withdrawn out of the end of the other tube by means of a windlass or the like. Simultaneously, with the removal of the protective tube A concrete is poured in the directing tube F and is firmly rammed with a rammer K (Fig. 4) which possesses a somewhat similar diameter to that of the directing tube and is fastened to a cable which 70 passes over a pulley suspended above the tube.

The process is continued until the protective tube is entirely withdrawn and the hole is left full of concrete.

What I claim is:

1. A process of pile driving and excavating consisting in driving a pile surrounded by a protecting tube, drawn by said driving pile, drawing said pile, inserting a filling tube of thinner material and smaller in external diameter than the internal diameter of said protecting tube inside the latter so as to be placed out of contact with the protecting tube, placing concrete in small quantities into said filling tube and ramming said concrete so as to set said filling tube into vibration with simultaneous raising of tubes until they are entirely taken out of the ground and the space thus left is filled 100 with concrete.

2. A process of pile driving and excavating, consisting in driving a pile surrounded by a protecting tube, withdrawing said

pile, inserting a filling tube of thin material and smaller in external diameter than the internal diameter of said protecting tube inside the latter, so as to be spaced out of contact with the protecting tube, filling in concrete into said filling tube and ramming said concrete so as to set said filling tube into vibration.

In testimony whereof I have signed my name to this specification in the presence of 10 two subscribing witnesses.

DMITRY NICOLAJEWITSCH ALEXEEFF.
